UNITED STATES PATENT OFFICE.

JOHN A. HURLEY, OF ERIE, PENNSYLVANIA, ASSIGNOR TO THE F. F. ADAMS CO., OF SAME PLACE.

CORK-PULLER.

SPECIFICATION forming part of Letters Patent No. 350,308, dated October 5, 1886.

Application filed June 26, 1886. Serial No. 206,301. (No model.)

To all whom it may concern:

Be it known that I, JOHN A. HURLEY, a citizen of the United States, residing at Erie, in the county of Erie and State of Pennsylvania, 5 have invented certain new and useful Improvements in Cork-Pullers; and I do hereby declare the following to be a full, clear, and exact description of the invention, such as will enable others skilled in the art to which it appertains 10 to make and use the same.

This invention relates to machines for pulling corks from bottles; and it consists in certain improvements in the construction thereof, as will be hereinafter fully set forth, and pointed 15 out in the claim.

My device is illustrated in the accompanying drawings as follows:

Figure 1 is a side elevation of the device, with parts broken out to show construction. 20 Fig. 2 is a perspective view, enlarged size, of the plunger B detached from the machine.

The construction of the machine is as follows:

A is a barrel having a flaring mouth to receive the nose of the bottle. A' is a bracket 25 supporting said barrel. a is an arm extending from said barrel, and is adapted to receive the journal or fulcrum d of the lever D. The barrel A, bracket A', and arm a are cast together in one piece. In the barrel by the side 30 of the arm a there is a slot, a', which is formed therein at the time of casting.

B is a hollow plunger, which fits in the barrel A, and has on one side of it rack-teeth b formed in it. These cogs or teeth are sunken, 35 and do not interfere with the movement of the plunger within the barrel.

On the shaft or fulcrum d of the lever D there is secured a segment-gear, D', which enters the slot a' and engages the rack b. It will 40 of course be seen that as the lever D is vibrated the plunger B will be reciprocated.

C is a corkscrew-stem, which is journaled in the plunger B, and is free to move vertically. On its lower end is a corkscrew, C², and on its 45 upper end a crank, C', by which it can be revolved.

The operation of the device is as follows: The corked bottle is placed with its nose in the flared opening at the lower end of the 50 barrel. This raises the corkscrew C², the

stem C, and the crank C' up. By revolving the crank the corkscrew is driven into the cork, and when it is in the crank will rest on top of the barrel, as shown in Fig. 1. The lever D is then drawn up, and this lifts the 55 plunger up, and it carries the crank, stem, and corkscrew up, and draws the cork out of the bottle up into the barrel.

In previous applications by me now pending in the Patent Office, filed October 5, 1885, 6c No. 179,044, and April 10, 1886, No. 198,471, I have shown a barrel, plunger, and corkscrew similar to the one here shown; but the means for raising the plunger is different. The advantages of this construction over the 65 former is that there are fewer parts and the cost of construction is much less; and, also, the leverage in lifting the cork is the same at all positions of the lever, and a longer transverse movement of the plunger may be had so that 70 longer corks can be pulled.

I do not claim as invention the substitution of one well-known form of lever for another, broadly considered. My invention consists in the construction necessary to embody such a 75 substitution.

I am aware of the patent to Richardson *et al.*, No. 206,134, July 16, 1878, cork-extractors, and therefore do not wish to be understood as claiming any part of that construction. 80

What I claim as new is—

In a cork-puller, the combination, substantially as herein set forth, of the barrel A, having therein the slot a', the plunger B, fitting in said barrel and having on its surface 85 opposite said slot a series of rack-teeth, b, sunk in its surface, the lever D, fulcrumed near said slot a' and having thereon a segment-gear, D', which enters said slot and meshes with the rack-teeth on said plunger, the corkscrew stem C, journaled in said plunger, and the cranks C', connected with said stem and seated on said plunger.

In testimony whereof I affix my signature in presence of two witnesses.

JOHN A. HURLEY.
